UNITED STATES PATENT OFFICE.

EDGAR MOTT BOTTOOME, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A PLATE OR SIMILAR ARTICLE

Application filed July 29, 1925. Serial No. 14,251. Term of patent 14 years.

To all whom it may concern:

Be it known that I, EDGAR MOTT BOTTOOME, a citizen of the United States of America, and resident of Moundsville, county of Marshall, and State of West Virginia, have invented a new, original, and ornamental Design for a Plate or Similar Article, of which the following is a specification, reference being had to the accompanying drawings, in which the figure is a top plan view of a plate of conventional form embellished with my new design and illustrating the latter.

I claim:

The ornamental design for a plate or similar article, as shown.

EDGAR MOTT BOTTOOME.
